UNITED STATES PATENT OFFICE.

EDWARD F. CRANE, OF NEWARK, NEW JERSEY.

REINFORCED CONCRETE CONSTRUCTION.

1,087,644.

Specification of Letters Patent. Patented Feb. 17, 1914.

Application filed April 30, 1908. Serial No. 430,103.

To all whom it may concern:

Be it known that I, EDWARD F. CRANE, citizen of the United States, and resident of Newark, in the county of Essex and State of

5 New Jersey, have invented certain new and useful Improvements in Reinforced Concrete Construction, of which the following is a specification.

My invention relates to that type of metallic-reinforced concrete construction formed with hollow spaces therein and particularly adapted for use in floor and ceiling construction.

The invention has for one of its objects to 15 improve reinforced concrete construction of the type referred to by combining with the concrete a metallic-reinforcing structure of a character to impart a maximum strength to the concrete with a minimum weight of 20 metal.

The invention has for a further object to provide an improved metallic-reinforcing structure for concrete construction that may be made up as a complete unitary structure 25 independent of the concrete, whereby it may be made up in any desired or convenient place and be capable of subsequent association with the concrete without further work than the mere placing of the same in position to have the concrete poured or otherwise located thereabout.

These, and other objects of my invention to be hereinafter referred to, are attained by means of the novel features of construction 35 and combinations of parts illustrated in the accompanying drawings forming part of this specification, in which—

Figure 1 is a perspective view of a metallic-reinforcing structure for concrete construction embodying certain features of my invention. Fig. 2 is a perspective view of a concrete body having associated therewith the metallic-reinforcing structure shown in Fig. 1. Fig. 3 is a detail view in section and elevation of a floor and ceiling construction embodying another form of my invention. Fig. 4 is a transverse vertical section of the same taken on a line through the center of one of the arch-plates. Fig. 5 is a detail view in section and elevation of a floor and ceiling construction showing another form and application of my invention. Fig. 6 is a further detailed view in section and elevation of the same looking from the right in Fig. 5. Figs. 7 to 20 inclusive show various modifications and applications of my invention, all to be hereinafter referred to in the detailed description of the invention which follows.

A reinforcing structure embodying my invention will preferably comprise a series of 60 alternating arch-plates and bars arranged parallel with each other, and a plurality of supporting strips arranged transversely beneath said arch-plates and bars and suitably secured thereto, as shown generally in Fig. 1. The arch-plates will preferably be formed of sheet metal and will also preferably be provided with a stiffening rib or ribs and with a broken or interrupted surface at 65 or adjacent to their lower side to promote the adhesion thereto of the concrete or other cementitious material. These arch-plates may also be variously formed in cross-section to meet the requirements of either the maker 70 or user. For instance, in Figs. 1 and 2, each arch-plate 2 is of true arch form and provided with a lower or base wall 3 resting upon the transverse supporting strips 4, to which latter the arch-plates are secured by 75 suitable fastening means, such for instance as wire-lacings 5 passed through suitable openings in the said parts as shown. Instead of the lower or base wall of the arch-plate being formed by a part or extension of the 80 plate itself, however, as shown in Figs. 1 and 2, it may be formed by transversely-extending wire lacings or rods as shown in Figs. 11 and 12, which illustrate a bottom and end view respectively of an arch-plate 85 so constructed, the arch-plates being indicated at 6 and the wire-lacings or rods at 7. This lower or base wall serves to stiffen and strengthen the arch-plate by preventing liability of spreading or contracting of the 90 same at its base, and in any event will preferably be formed with a broken or interrupted surface to promote the adhesion thereto of the concrete or other cementitious material; this broken or interrupted surface, 95 where the lower or base wall is formed by a part or extension of the arch-plate itself, being provided by punching or otherwise forming openings 8 in the metal as shown. 100

In some instances, in lieu of forming single arch-plates, I form a plurality of them, either by connecting two or more together at their adjacent longitudinal edges, as shown in Fig. 20, or by forming the same of a single piece of metal as shown in Figs. 8, 9 and 110

10; this latter form, when made up with a single underlying base plate 9 as shown, being the preferable form of construction in that it provides a more stiff and rigid structure. One of the advantages of this double form of arch-plate, other than the feature of strength and rigidity referred to, is that it necessitates the use of less false-work in building up the concrete construction in that 5 it is necessary to support the double arch-plates only at their outer base edges. It will of course be understood that this double arch structure may be formed in any desired manner, the same as shown in Fig. 8 being 10 formed by bringing the edges of the sheet metal together at the upper side of the base plate, and as shown in Figs. 9 and 10 said edges being brought and secured together at the center of the base plate itself. 15

20 In making up these arch-plates of sheet metal I also preferably provide the same with stiffening ribs which may extend longitudinally of the plates, as indicated at 10 in Figs. 1, 2 and 5 and at 11 in Fig. 17, and 25 transversely of the plates, as indicated at 12 in Fig. 14, which latter illustrates a side elevation of an arch-plate so formed. Also, the arch-plates will preferably be formed at their ends with radially-extended flanges 13 30 as an additional stiffening means, as shown in Figs. 15 and 16 which illustrate an end and side elevation respectively of an arch-plate so formed.

The arch-plates will usually and preferably have a true arch form as shown and described, but they may be otherwise and variously formed provided they serve the same purpose. For instance, in some cases I may employ tubing, as indicated at 14 in 40 Fig. 18, the upper part of which provides the arch, and the lower part of which provides a lower or base wall to the arch, which lower or base wall will also have a broken or interrupted surface formed by providing 45 perforations 15 therethrough to promote the adhesion thereto of the concrete.

In some instances I also form these arch-plates with a plurality of chambers in order to further increase the non-conducting properties of the same. This may be accomplished by providing the arch-plates with partitioning walls of any suitable character, one form of which is shown as an inner tube 16 supported about centrally within 55 the outer plate by means of interposed strips 17. The same result may also be accomplished by associating together a series of tubes as shown in Fig. 19, the outer walls 18 of which would serve as the arch-plate, and 60 the inner or adjacent walls 19 of which would serve as the partitioning walls.

The arch-plates as hereinbefore described are preferably secured to the transverse stiffening strips 4 by wire-lacings 5, and the 65 reinforcing bars, indicated at 20, are also

preferably secured to said strips 4 in their position between the arch-plates by similar means, as indicated at 21.

The building of reinforced concrete construction embodying my invention will vary somewhat according to the character of the work. For instance, in building up a slab or a beam as shown in Fig. 2 for floor or other construction, a thin bed of concrete *c* may first be laid upon a suitable false-work, indicated at 22, then upon this thin bed of concrete will be placed the metallic-reinforcing structure, after which the concrete *c* will be poured about and above said structure, the whole forming a metallic-reinforced concrete slab or beam having a series of arches 23 with intermediate beams 24 which are substantially rectangular in cross-section; the arches being supported and reinforced by the metallic arch-plates and the beams being supported and reinforced by the metal bars, the latter being located at the lower or tension side of the beam in the general plane of the base of the arch-plates and the whole metallic structure being so disposed within the concrete as to impart a maximum strength thereto with a minimum weight of metal. The several parts of the metallic-reinforcing structure of the slab or beam being secured in fixed relation to each other prior to their association with the concrete, will maintain such relation during the subsequent association therewith of the concrete and so assure perfect alinement of the arches and beams. In the building up of this reinforced concrete construction, the ends of the arch-plates will preferably be closed or sealed to prevent the running thereinto of the concrete, and this sealing may be effected by fitting a suitable plate 25 within the end of the arch-plate. The position of this sealing plate within the arch-plate will vary according to conditions: for instance, for very light work the sealing plate may be located at the extreme 100 end of the arch, as indicated at *a* in Fig. 1, in which event no concrete will enter the arch-plate, or for heavy work or where the end of the arch is intended to provide a bearing, the said sealing plate will be set a 105 short distance into the arch, as indicated at *b* in Fig. 1, so as to permit the concrete entering and forming a solid end to the arch. These sealing plates also serve as a means to support the arch-plates transversely and add to the compressive strength of the 110 same.

The layer of concrete or other cementitious material at the under side of the arch-plates is usually quite thin and therefore 115 liable to crack and drop off when exposed to high heat for any considerable time. Because of this and in order to add to the fire-proof qualities of the construction, I sometimes provide a thin bed of concrete 26 with- 120

in the metal arch-plates and at the bottom thereof, as shown in Fig. 1, this bed of concrete being poured or otherwise located within the arch-plates prior to the edges of the two side sections of the latter being being brought and secured together at the top of the arch as shown. In order to support this bed 26 independent of the bottom wall of the metal arch whereby it will remain intact and in position in the event of the bottom wall of the metal arch becoming distorted in any way under the action of the heat, I form the side walls of the arch-plates adjacent to their base with inwardly-extended shoulders 27 which serve to vertically support the bed 26 at its edges. The arch-plates being thus formed with the inwardly-turned shoulders 27 at their base, also thereby provide for the formation of laterally-projecting shoulders 27' in the concrete which extend beneath the said shoulder portions 27 of the arch-plates and operate to vertically support said arch-plates and also the concrete bed or slab 26 therein.

The use of the concrete bed 26 within the metal arches is also of advantage in that it avoids the necessity of applying any cementitious material to the under side of the metal arches when those arches are provided with lower or base plates, which latter in such case may be plain, or be stamped or otherwise formed to present an ornamental appearance. This is of special advantage inasmuch as it avoids the expense of plastering after the false-work is removed.

In some instances it may not be necessary or desirable to connect together the metallic-reinforcing elements as a unitary structure prior to their association with the concrete, in which event the metal arch-plates and bars may be separately handled and positioned during the course of the construction, as indicated in Figs. 3 to 7 inclusive, in which the transverse supporting and tie strips 4 are omitted. In the construction shown in Figs. 3 and 4, a concrete slab, reinforced by metal arch-plates 27 and bars 28 in accordance with my invention, is formed to rest upon a concrete beam 29 also reinforced by a metal arch-plate and bars in accordance with my invention. In this construction I also show a second series of air chambers 30 running transversely to the chambers 23 and in position above the same, whereby the construction will be lightened without reducing the strength of the same. In the construction shown in Figs. 5 and 6, a concrete slab, also reinforced in accordance with my invention, is formed for support by steel beams 31 and preferably for support on a concrete ledge 32 located on said beam. In this instance the arch-plates, instead of being provided with base plates as a part of the same, are closed at their under side by metal lathing 33 to which

the plaster or other cementitious material is adapted to be applied subsequent to the removal of the false-work 34. In the construction shown in Fig. 7, concrete beams 35 reinforced in accordance with my invention are molded or made up separately and then placed in desired position and grouted therebetween, as at 36; this method of construction being desirable in that no expensive machinery or collapsible core construction is required. In making up these several different forms of construction I will usually and preferably employ anchor-bars 37 which will connect at their lower end with the underlying base of the arch-plates and extend at their upper end into the concrete and operate to support and prevent sagging of the said base.

In some instances it may be desirable to give the sheet metal arch-plate an added strength and stiffness, and as a simple and effective way of doing this I provide the same with a juxtaposed layer of stiffening material, as indicated at 38 in Fig. 7, which may be of wood, metal, concrete, or other material.

Among the advantages derived from the use of the metal arch-plates as described is that they avoid possibility of weakness in the concrete beams that might result from the concrete running into the air spaces or chambers, as does sometimes occur in these constructions employing terra-cotta blocks or similar readily breakable material for providing the air spaces or chambers. A further and important advantage derived from the use of the metal arch-plates is that they increase the compressive strength of the concrete by reason of the location of the upper part of the plates adjacent to the upper surface of the concrete slab; this compressive strength afforded by the arch-plates being materially increased by reason of the longitudinal stiffening rib or ribs with which they are provided.

In producing the above described reinforced concrete construction it is to be understood that applicant is not to be limited in his invention to the order of the steps as described in building up this invention, but the order may be arranged in any practical manner to produce with greater accuracy and for the purpose of convenience this reinforced concrete construction.

What I claim is:

1. The combination with a cementitious body, of a reinforcing element, an arch plate formed of a continuous sheet of metal and supported by said reinforcing element, a bed of cementitious material contained within said arch plate, and a longitudinal opening located at the top of the arch plate whereby cementitious material may be introduced therein for the purpose set forth.

2. A cementitious body having a metallic reinforcing structure comprising an arch-plate having inwardly extended shoulders at its opposite sides, and a bed of cementitious material contained within the arch-plate and engaged by the said shoulders therein.

3. A metallic reinforced cementitious body comprising a series of alternating arches and beams, the arches being supported and reinforced by metallic arch-plates and the beams being substantially rectangular in cross-section and being reinforced by metallic bars embedded therein, and the said cementitious body being provided with a series of openings extending transversely of the arches therein.

4. A metallic reinforced cementitious body comprising a series of alternating arches and beams, the arches being supported and reinforced by metallic arch-plates having stiffening ribs and the beams being substantially rectangular in cross-section and being reinforced by metallic bars embedded therein, and the said cementitious body being provided with a series of openings extending transversely of the arches therein.

5. A cementitious body having a metallic reinforcing structure comprising an arch-plate having inwardly extended shoulders at its opposite sides, and a bed of cementitious material contained within the arch-plate and engaged by the said shoulders therein; the said cementitious body having a part thereof engaging the said shoulders of the arch-plate at the outer side thereof to vertically support and retain the arch-plate within the cementitious body.

6. A cementitious body having a metallic reinforcing structure comprising an arch-plate having inwardly extended shoulders at its opposite sides, and a bed of cementitious material contained within the arch-plate and engaged by the said shoulders; the said

cementitious body having a part thereof engaging the said shoulders of the arch-plate at the outer side thereof to vertically support the arch-plate within the cementitious body.

7. That improvement in the art of producing a reinforced concrete construction which consists in forming an arch plate of a continuous sheet of metal open at the top thereof from end to end, placing the arch plate in position, introducing cementitious material into said arch plate through the opening in the top onto the base of the arch plate, closing the said opening, and then filling in concrete around the arch plate.

8. That improvement in the art of producing a reinforced concrete construction which consists in forming an arch plate of a continuous sheet of metal open at its top continuously and in a longitudinal direction, introducing cementitious material into said arch plate through the opening in the top onto the arch plate base, closing said opening, placing the arch plate in final position, and then filling in concrete around the arch plate.

9. That improvement in the art of producing reinforced cementitious construction which consists in forming an arch plate of a continuous imperforate sheet of metal open at its top, introducing cementitious material onto the base of the arch plate through said open top, closing the top of the arch plate, placing the arch plate in its final position, and filling in cementitious material around the arch plate.

Signed at New York, in the county of New York, and State of New York, this 28th day of April, A. D. 1908.

EDWD. F. CRANE.
